UNITED STATES PATENT OFFICE.

DAVID JOHNS, OF BROOKLYN, NEW YORK.

DESIGN FOR A COAL-SCUTTLE.

SPECIFICATION forming part of Design No. 22,607, dated July 11, 1893.

Application filed May 10, 1893. Serial No. 473,733. Term of patent 14 years.

To all whom it may concern:

Be it known that I, DAVID JOHNS, a citizen of the United States, residing at Brooklyn, Kings county, State of New York, have invented a certain new and useful Design for Coal-Scuttles, &c., of which the following is a specification, reference being had to the accompanying drawings, forming part hereof.

My invention consists of a certain new, useful and original shape or configuration of an article of manufacture, to wit., a coal scuttle or coal hod.

My invention is shown in the accompanying drawings, of which Figures 1 and 2 are perspective views, showing in different positions a coal scuttle embodying my invention.

The characteristic feature of my invention

is the long, sloping and approximately flat front wall *a*, and the short nearly vertical rear wall *b*. Both front and rear walls are intersected at points above their lower parts by the supporting rim *c*. The side walls *d*, *d* are nearly vertical and approach each other toward the front of the scuttle. A handle *e* is attached to said side walls, said side walls having projections *f*, *f*, in front of said handle.

What I claim, and desire to secure by Letters Patent, is—

The design for a coal scuttle consisting of the design substantially as shown.

DAVID JOHNS.
